UNITED STATES PATENT OFFICE.

LOUISE J. PERRY CROOMS, OF ORLANDO, FLORIDA, ASSIGNOR OF ONE-HALF TO WIL-
LIAM P. BUSH, OF JACKSONVILLE, FLORIDA.

HAIRDRESSER'S COMB.

Application filed November 4, 1921. Serial No. 512,935.

To all whom it may concern:

Be it known that I, LOUISE J. PERRY CROOMS, a citizen of the United States, residing at Orlando, in the county of Orange and State of Florida, have invented a new and useful Hairdresser's Comb, of which the following is a specification.

This invention relates broadly to an improved toilet article, but has more specific reference to one which may be conveniently termed a hair dresser's comb.

The principal object of the invention is to generally improve upon articles of this class by providing a comb having a handle 15 to permit it to be conveniently manipulated, together with an attachment for cooperation with the back of the comb to permit the hair to be passed between the back and attachment and then through the teeth for straightening it preparatory to dressing it.

More specifically speaking, it is another object of the invention to provide a pivotally mounted detachable presser bar for use in connection with a comb, the bar and 25 comb both being composed of metal to permit them to be preheated so as to more effectively act on the hair when putting it in condition for dressing.

The various features and advantages of 30 the invention will become apparent by reading the following description.

In the accompanying drawings forming a part of this specification and in which like numerals are employed to designate like 35 parts throughout the same:

Figure 1 is a side elevation of a hair dresser's comb constructed in accordance with this invention.

Figure 2 is a perspective view of the 40 presser bar.

Figure 3 is a perspective view of the comb with the bar detached.

Figure 4 is a top plan view of the comb.

Figure 5 is a detail perspective view of 45 the fulcrum bracket.

In carrying out the invention, I employ a metallic comb 1 having a flat faced back 2 and a plurality of closely spaced teeth 3 between which the hair is drawn in the usual 50 manner. It is to be noted that the upper face of the back 2 is flat as indicated at 4 for a purpose to be hereinafter specified. For convenience of manipulation, the back is extended beyond the teeth as indicated at 5 to

provide a handle. Inasmuch as the comb 55 is intended to be heated before being used, it is desirable to prevent burning of the operator's fingers. Therefore, a sectional hand-grip 6 of insulation material is connected with the handle as shown. While on this handle, it may be mentioned that it is equipped adjacent the teeth with a transverse slot 7 and with a screw threaded hole 8 which extends through its bottom and into this slot. As is obvious, the laterally directed lower end 10 of a fulcrum bracket 9 is intended to be inserted in this slot and held therein by means of a set screw 11 which is screwed against it. It is to be noted that the upper end of the bracket 9 is cylindrical 70 and tapered as indicated at 12 and this provides a journal which is rotatable in a bearing opening 13 formed on the intermediate portion of a presser bar 14. It may be mentioned here that the presser bar is readily detachable from this journal so that it can be removed when desired. Although the presser bar could be constructed otherwise, it has its outer end downturned as indicated at 15 and this downturned end rests 80 against the flat face 4 of the back of the comb when the bar is in use. By directing this end of the bar downwardly as shown and spacing the journal of the fulcrum bracket above the back of the comb, a space is provided between the bar and said back to permit the hair to be drawn therethrough. Referring now to the opposite end of the presser bar, it will be seen that the portion inward of 85 the aforesaid bearing is directed slightly upward to provide a finger-piece 16. In practice a suitable spring 17 is interposed between the finger-piece and aforesaid handle to maintain the laterally directed outer end of the presser bar in contact with the back of the comb and to maintain the bar in yieldable contact with the hair when the appliance is in use.

In practice, the comb and presser bar are heated to the desired degree with any suitable means and a quantity of the hair is passed through the teeth of the comb in the usual way and over the back thereof. At this time, the presser bar is moved out of engagement with the back of the comb 105 by pressing downwardly on the finger piece, and as soon as it is released, it comes into engagement with the hair and compresses it

slightly between itself and the flat face of the back of the comb. Hence, it is obvious that when the comb is now drawn further through the hair, the latter is straightened and acted on through the medium of the heated parts to place the hair in good condition to enable the hair dresser to work expeditiously with the help of this device. The invention is particularly advantageous for untangling the hair due to the fact that it spreads it so that it will be more evenly distributed as the teeth of the comb are drawn therethrough. In the event that the presser bar is not needed, it can be readily removed. This is also true of the fulcrum bracket.

From the foregoing description and drawings it is evident that I have evolved and produced a unique comb for use by hair dressers and the like. It is particularly advantageous for straightening and treating the hair and placing it in good condition preparatory to dressing it. The several parts are separable as intimated so that the device may be used with or without the presser means. Also, due to the extreme simplicity of the invention, it is rendered comparatively inexpensive to both the manufacturer and the user. These and other advantages and features of the invention have doubtless been made apparent and a more lengthy description is therefore deemed unnecessary.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the

scope of the invention as claimed may be resorted to if desired.

I claim:

1. In a hair dresser's appliance, a comb having a handle, and a presser bar pivotally mounted upon the handle and spaced from the back of the comb to provide a space through which the hair is drawn.

2. In a hair dresser's appliance, a comb having its back extended to provide a handle, a bracket supported on said handle and provided with a journal, and a bar spaced from the back of the comb for pressing the hair against the back, said bar being provided with a bearing opening receiving said journal.

3. In a hair dresser's appliance of the type specified, a comb, a presser bar associated with and spaced slightly from the back of the comb, said bar having a finger-piece, and means for pivotally connecting the bar with the comb and spacing the former from the back of the latter.

4. In a hair dresser's appliance, a comb having a slotted extension, a bracket having a portion received in the slot of said extension, said bracket including a journal, and a spring pressed presser bar associated with the back of the comb, said bar having a bearing opening in which said journal is received.

5. In a hair dresser's appliance, a comb having its back extended to form a handle, said handle being provided adjacent the teeth with a transverse slot, a bracket having its laterally directed lower end received in said slot, said bracket including a journal extending over the back of the comb in spaced relation, and a presser bar spaced above the back and equipped with a bearing opening in which the journal is received.

LOUISE J. PERRY CROOMS.

In the presence of—

M. A. SLOAN,
BESSIE MINER.
